UNITED STATES PATENT OFFICE.

MARGARET N. ROSS, OF AUBURNDALE, MASSACHUSETTS.

RECEPTACLE.

1,216,502.

Specification of Letters Patent. Patented Feb. 20, 1917.

Application filed February 19, 1915. Serial No. 9,219.

To all whom it may concern:

Be it known that I, MARGARET N. Ross, a citizen of the United States, and a resident of Auburndale, county of Middlesex, 5 and Commonwealth of Massachusetts, have invented certain new and useful Improvements in Receptacles, of which the following is a full, clear, and exact specification.

This invention relates to that class of 10 receptacles or boxes wherein the front has a vertical slot therein, and an easily opened narrow top, whereby the contents can be conveniently removed by the application of the forefinger of holder's hand through the 15 vertical slot, and an upward pressure of the tip of the finger against a portion of the contents.

What I am endeavoring to accomplish is the effecting of means for preserving the 20 contents from climatic conditions, particularly when the same are cigarettes and especially liable to lose their flavor and become too dry.

Referring to the drawings forming part 25 of this specification, Figure 1 is a perspective view of the box composing a portion of my improved receptacle. Fig. 2 is a horizontal section of the same containing the remaining elements of my invention. 30 Fig. 3 is a perspective view of the lining for the box. Fig. 4 is a perspective view of the lining having a section thereof made separable. Fig. 5 is a perspective view of the separable section.

35 The box alone comprises a back 1, front 2 having a vertical slot 3 therein, bottom 4, ends 5 and hinged top 6. Thus made, the flavor and moisture of the contents will escape to a greater or less extent, depending upon climatic conditions, through the slot 3.

The lining is made of thin and preferably moisture-proof paper, as waxed paper, foil-paper and the like, and comprises a back 45 10, front 11 having a vertical slot 12 therein, a bottom 13, a top member 14 and a frontal lining 15. These parts may be integral, as illustrated in Fig. 3, or the frontal lining and top may be separate, as shown in Figs. 50 4 and 5, and the back 10 may be provided with end flaps 17, as shown in Fig. 3.

In case the receptacle is designed for 55 cigarettes, the latter are placed between the front and back 11, 10 parallel with the bottom 13. The front is then turned down flat upon the cigarettes, and the frontal

lining 15 is folded down upon the front. The same is then slid down into the box, with the slot 12 parallel with the slot 3 but separated therefrom by the frontal lining 15, as shown in Fig. 2.

As is evident, the space between the paper front 11 and the box front 2 forms in effect a pocket for the frontal lining 15, so that if the latter falls away from one front, it 65 contacts with the other, and, since the paper elements fit snugly between the box ends 5, renders the slots incapable of permitting the escape of moisture.

The ends or flaps 17 serve to retain the 70 cigarettes in place more perfectly as the parts are being slid into the box.

The advantage in having the frontal lining 15 separate from the parts 10 and 11 is that said lining may be made of heavier 75 paper, or even card, while the remainder are of thin paper. Further, the frontal lining 15, and the connected top 14 can be more easily drawn out to give access to the contents through the slots, than can the 80 integral lining. Further, the card lining 15 can be returned to its original place, if desired to preserve the cigarettes for a further period.

It should be noted that the slot 12 in the 85 paper front 11 does not reach to the bottom of the latter. The purpose of this is to insure against the escape of moisture between the adjacent edges of the frontal lining and the bottom 4 of the box, as would be the case were said slot to extend to the same point as does the slot 3. When the lowermost cigarette is reached, the pressure of the finger easily tears the thin paper front thereat and reaches the object behind. 90 95

If desired, the box may be made somewhat fancy and comparatively expensive, and the cigarettes may be shipped in the paper lining suitably sealed by internal revenue stamps, and slid into the box as needed. 100

What I claim is:

1. The combination with a box having a vertically slotted front and a movable top, of a lining comprising a slotted front, a bottom, a back and a frontal lining designed 105 to fit between the box front and the lining front.

2. The combination with a box having a vertically slotted front and a movable top, of a lining comprising a slotted front, a 110 bottom, a back, a top member and a frontal lining, the front, bottom and back being

integral, and the top member and frontal lining being integral.

3. The combination with a box having a vertically slotted front and a movable top, of a lining comprising a slotted front, a bottom, a back and a frontal lining, the slot in the lining front being spaced from the bottom.

In testimony that I claim the foregoing invention, I have hereunto set my hand this 16th day of February, 1915.

(Mrs.) MARGARET N. ROSS.
